PORATION OF MASSACHUSETTS

WINDOW SCREEN

Application filed October 21, 1931, Serial No. 570,165, and in Canada March 19, 1931.

The present invention relates to window screens which are adjustable for various sizes of windows. It is especially desirable in screens of this type in order to facilitate manufacture and assembly of the screens, that the individual sections of the screens be similar, and that the completed sections be readily connected together for use and it is accordingly an object of the present invention 5 to provide window screens which incorporate these advantages. According to the invention, the individual screen sections are duplicates and are provided on opposite edges with channels and slides which inter-engage 10 with channels and slides on the other section of each pair of screens. The slides and channels are so arranged that the individual sections may be directly connected together in 15 their completed form to provide a completed screen without the necessity for further structural changes. Other and further objects and advantages of the invention will appear from the following detailed description taken in connection with the accompanying 20 drawing in which:—

Fig. 1 is a perspective view of an assembled screen partly in section, with portions of the screening removed.

Fig. 2 is a cross-section on the line 2—2 of Fig. 1.

Fig. 3 is a cross-section on the line 3—3 of Fig. 1.

Fig. 4 is a perspective view, partly in section, substantially along the line 4—4 of Fig. 1.

Fig. 5 is a perspective view of a portion of one of the screens.

Fig. 6 is a plan view of an edge of the completed screen.

Like reference characters refer to like parts throughout the drawing.

Referring particularly to Fig. 1, the complete screen is made up of a pair of sections A and B which are each identical in construction. Because of the similarity of construc-

tion corresponding reference characters are applied to corresponding parts of each section and a description of one section will suffice for both. Each section consists of longitudinally extending top and bottom frame members 1, an outer end member 2 and an inner end member 3. The outer edge 4 of the end member 2 is folded over into engagement with the main portion of said member and the outer ends of the top and bottom frame members 1 are clamped between said folded edge 4 and the main portion of member 2. Similarly, the outer edge 5 of the end member 3 is folded over into engagement with the main portion of said member 3, and clamps between said folded edge and the main portion of said member the inner ends of the members 1, to form with the top and bottom members 1 and the other end member 2 the completed frame for each screen section.

As shown in Fig. 1, the screening material 6 which covers the frame is applied to the outer face of the section A and is secured at its opposite ends between the folded over edges 4 and 5 and the main portions of the members 2 and 3, the screening is also secured along its longitudinal edges to the frame members 1 by tongues 7 integrally formed with said frame members, said tongues 7 being displaced from said members and subsequently bent into engagement with the edges of the screening 6 (Figs. 2 and 3).

A pair of the individual screen sections A and B, above described, are arranged to be attached together to form a complete screen and to slide relative to one another, whereby the complete screen is adaptable to different widths of windows. To this end, the outer edges of the top and bottom frame members 1 of each screen section are provided respectively with channels 8 which extend the entire length of the members, all the channels 8 having the same cross-section. Referring particularly to Figs. 2 and 3, each channel 8

is offset from the plane of its member 1 with a rebent outer edge 9 lying substantially in the plane of the member 1. The inner end member 3 of each frame is provided at opposite ends, beyond the ends of the folded edge 5, with slides 10, which form extensions of said end member 3 and said slides 10 being bent to correspond substantially to the cross-section of the channels 8 may enter and slide within the channels 8 of opposed frame members 1, when two sections A and B are assembled.

In assembling a pair of screen sections to form a completed screen, one section A with its slides 10 projecting from the left hand side thereof is placed upon the oppositely facing section B with its slides 10 projecting from the right hand side thereof. In this position, the frame members 1 of the upper section A are alined with the frame members 1 of the lower section B, with the channels 8 in opposed relation and the edges 9 abutting. Thus, the slides 10 of each section are in register with the channels 8 of the opposed section. As indicated in dotted lines in Fig. 1, the end member 3 of the upper screen section A in this initial assembling position projects beyond the end member 2 of the under screen section B, with the outer edge of member 2, section B, substantially coinciding with the inner edge of the member 3 of the upper section A. Similarly, the end member 3 of the lower section B projects beyond the end member 2 of the upper section A, the inner edge of the member 3, section B, coinciding substantially with the outer edge of the end member 2, section A. From this initial position, movement of the sections A and B relative to one another in the plane of the screens permits the slides 10 which, as above stated, are in line with the opposing channels 8 to enter said channels. A completed screen, the sections of which are securely held together, as shown in Fig. 1, is thus formed.

Movement of the screen sections A and B in extending or lengthening the screen during adjustment thereof, is limited by engagement of the inner edge of the end member 3 of one section with the opposed inner edge of the end member 3 of the opposite section, as will be clear from a consideration of Fig. 1. After the screens have been assembled, protuberances or punched stops 11 are provided adjacent the outer ends of either or both of the longitudinal members 1 of one section (B as shown) in a position to engage with the slides of the opposite section A of the completed screen, thereby to prevent unintended separation of the screen sections during shortening or collapsing of the screen.

From the foregoing, it will be noted that each screen section is identical in construction with the other section and that the channels and slides are integral with the frame members forming the screen, the arrange-

ment being such that the sections may be independently formed and completed before said sections are assembled to form the completed screen.

We claim,

1. An adjustable screen comprising a pair of similar frame members each having channels formed along opposite longitudinal sides, cross strips connecting the adjacent ends of the said sides, slides formed on the opposite ends of one of said cross strips of each frame for engagement with the channels of the other frame and a projection integral with one of said frame members for engagement with a slide on the other frame to limit the relative movement of the frames in one direction.

2. An adjustable screen comprising a pair of similar frame members consisting of side and end members connected together, said side members each having a channel integrally formed along the outer edge thereof, slides formed on the extremities of one of the end members of each frame for engagement in the channels of the other frame, portions of the slides of one frame member being in alinement and engageable with portions of the slides of the other frame member in the completed screen to limit the relative movement of the frames in one direction.

3. An adjustable screen comprising a pair of similar frame members consisting of side and end members connected together, said side members each having a channel integrally formed along the outer edge thereof, slides formed on the extremities of one of the end members of each frame for engagement in the channels of the other frame, portions of the slides of one frame member being in alinement and engageable with portions of the slides of the other frame member in the completed screen to limit the relative movement of the frames in one direction, and means to limit the relative movement in the opposite direction.

4. An adjustable screen comprising a pair of similar frame members consisting of side and end members connected together, said side members each having a channel integrally formed along the outer edge thereof, with said channels extending throughout the length of said side members, slides formed on the extremities of one of the end members of each frame and projecting laterally beyond the outer edge of the end member for engagement in the channels of the other frame, portions of the slides of one frame member being arranged to engage with portions of the slides of the other frame member to limit the relative movement of the frames in one direction.

5. An adjustable screen comprising a pair of similar frame members consisting of side and end members connected together, said side members each having a channel integral-

ly formed along the outer edge thereof, said channels extending throughout the length of said side members, slides formed on the extremities of one of the end members of each frame and projecting laterally beyond the outer edge of the end member, said slides being spaced from and out of alinement with the adjacent channels in the same frame member for engagement in the channels of the other frame when said frame members are placed in superposed relation.
